(57) **CLAIM**

We claim the ornamental design for a barbecue assembly, as shown and described.

DESCRIPTION

FIG. 1 is a perspective view of a barbecue assembly of the present claimed design;

FIG. 2 is a top view of the barbecue assembly shown in FIG. 1;

FIG. 3 is a bottom view of the barbecue assembly shown in FIG. 1;

FIG. 4 is a front view of the barbecue assembly shown in FIG. 1;

FIG. 5 is a rear view of the barbecue assembly shown in FIG. 1;

FIG. 6 is a left side view of the barbecue assembly shown in FIG. 1; and,

FIG. 7 is a right side view of the barbecue assembly shown in FIG. 1.

Features shown in broken lines in the drawings form no part of the claimed design.

1 Claim, 4 Drawing Sheets

FIG. 2**FIG. 3**
